UNITED STATES PATENT OFFICE.

DAVID W. DE FOREST, OF BROOKLYN, ASSIGNOR TO DONALDSON BROTHERS, OF NEW YORK, N. Y.

LABELING PLUG-TOBACCO.

SPECIFICATION forming part of Letters Patent No. 254,285, dated February 28, 1882.

Application filed December 19, 1881. (No model.)

To all whom it may concern:

Be it known that I, DAVID W. DE FOREST, a citizen of the United States, residing in the city of Brooklyn, county of Kings, and State of New York, have invented certain new and useful Improvements in Labeling Plug-Tobacco, fully described and represented in the following specification and the accompanying drawings, forming a part of the same.

- 10 The object of my invention is to overcome certain objections current in various tobacco-markers in present use, and to enable the manufacturer to use either metal or non-metallic substances for the purpose of marking plug 15 or other styles of tobacco, and to be known as the "Riveting process." When a flat piece of metal is used as a label, with projections at right angles with its surface, they perforate the wrapper of tobacco, and the fluid or juice 20 of the tobacco-filler is liable to ooze out when under pressure and injure the appearance of the plug. Should a flat piece of metal be used with designs upon its surface, they do not adhere to the plug reliably without prongs or 25 projections. When card-board or other materials are used as labels they are liable to be displaced during the process unless tacked in their respective positions. Even if they are gummed, the oily nature of tobacco prevents 30 them from properly adhering.

To obviate the aforesaid faults I have invented the following improvements:

Having reference to the drawings, Figure 1 is a plan view of a plate either of metal or 35 other material, with a hole or aperture through it, as represented at A.

Fig. 2 is a sectional side view through line $\alpha\alpha$ of Fig. 1.

Fig. 3 represents the plate B with plug-to- 40 tobacco C after pressure, showing the elevation D of tobacco C, having receded or raised into the recess A of plate B by the pressure, and which will be called the "rivet."

Fig. 4 represents the plug as prepared for 45 the label.

Fig. 5 represents the label F, of any stiff material, provided with a hole, E, of a diameter to pass over rivet D in plug C of Fig. 4.

Fig. 6 represents plug C, with label F over 50 rivet D, and showing rivet D as elevated

slightly above the surface of label F and ready for the pressure for completing the affixing of the label.

Fig. 7 is a plate without hole A of Fig. 1.

Fig. 8 represents plate B of Fig. 7 resting 55 on rivet D, with label F in position on plug-tobacco C for completion by pressure.

Fig. 9 represents plug C, label F, and plate B after pressure.

Fig. 10 represents the plug of tobacco com- 60 pletely labeled, with label imbedded in the same.

Fig. 11 is a partial longitudinal sectional view of a finished plug, showing the tobacco overlapping the upper surface of the edges of 65 the label to hold or rivet it.

It will be readily observed that as the rivet D of tobacco is pressed by plate B, Fig. 9, so firmly against the inner circle of the label F, and even overlaps the surface of the label to 70 some extent, as at points G, the label is affixed rigidly to the plug without perforating the wrapper.

The process of applying the labels is preferably done in the finishing-pots familiar to all 75 manufacturers of tobacco.

Having described my invention, what I claim is—

1. A plug of tobacco having a flat label riveted thereto by a rivet formed of and integral with the body of the plug, substantially 80 as shown and described.

2. The method of attaching labels to plug-tobacco which consists in forming a projection on the surface of a plug of tobacco, then placing a flat perforated label of less thickness than the height of the projection over said projection, and then subjecting the plug to pressure, so that the label will be riveted to the plug, and so that the outer surface of label, 90 rivet, and plug will all be in the same plane, substantially as shown and described.

In testimony that I claim the foregoing I have hereto set my hand this 9th day of December, A. D. 1881.

DAVID W. DE FOREST.
